UNITED STATES PATENT OFFICE.

HUDSON A. TEDMAN, OF GALESBURG, ILLINOIS, ASSIGNOR TO WINSLOW BOILER & ENGINEERING COMPANY, OF GALESBURG, ILLINOIS, A CORPORATION OF ILLINOIS.

FUEL-BURNING APPARATUS.

Application filed November 20, 1924. Serial No. 751,006.

This invention relates to improvements in apparatus for burning liquid fuel or the like, and has for its object to provide a drain and safety cut-out system which may be readily attached to and removed from the balance of the apparatus. Another object consists in the provision of a new and improved safety cut-out device.

These and other objects are more fully described in the following specification and shown in the accompanying drawings, in which—

Fig. 1 is a side elevation of apparatus embodying my invention.

Fig. 2 is a vertical section through one end of such apparatus.

Fig. 3 is an inverted plan or bottom view of the apparatus shown in Fig. 1.

Fig. 4 is a plan view of the collecting cups and drain pipes.

Fig. 5 is a perspective of the locking means.

Fig. 6 is a vertical transverse section along the line 6—6 of Fig. 1.

Fig. 7 is a similar view along the line 7—7 of Fig. 1.

Fig. 8 is a similar view along line 8—8 of Fig. 1.

Fig. 9 is a vertical section drawn to an enlarged scale along the line 9—9 of Fig. 8.

Fig. 10 is a side elevation of the cut-out switch and bucket showing the switch in position opening the motor circuit.

Fig. 11 is an inverted plan view of the switch and actuating member, the latter being pivoted out of operative position.

Fig. 12 is a perspective of the switch actuating bucket and arm.

Like numerals refer to like elements throughout the drawings, in which 10 designates generally the main casing containing certain functioning units of a liquid fuel burning apparatus, and serving as a conduit for air supplied from the motor blower 11 to the combustion chamber or firepot 12 which is supported upon the brick or masonry foundation 13. Adjustable pedestals 14 at the opposite end of the casing assist in the support of the apparatus. Leading from the firepot 12 at the rear end thereof are the drain passages 12^a. Located therebeneath are the cup or sump members 15, one at each side of the apparatus as shown in Fig. 6, for example. Leading rearwardly from each of the cups 15 is a drain pipe 16, which com-

municates with the sealing member 17 shown in detail, for example, in Fig. 9. The member 17 comprises a reservoir 17^a, an inlet port 17^b, an outlet port 17^c, and a third port 17^d. A partition 17^e depends into the reservoir 17^a beneath the level of outlet port 17^c. Between the sealing members 17 extends a cross pipe 19, which is provided with an enlarged cup portion 19^a intermediate its extremities, open at the top and in alignment with the drain port 10^a at the bottom of casing 10. From one of the sealing members 17^a extends the spout 17^f normally located over a collecting bucket or receptacle 20, which is suspended by links 21 from a spring arm 22. This spring arm is pivoted to the under side of the casing at 22^a, and limited in its movement by the guard strip 23 secured to the under side of the casing. Located in the casing is the switch 24 in circuit with the electrically actuating apparatus and opening the same with the normally spring extended button 24^a in extended position, as shown in Fig. 10. When the arm 22 is in assembled position and the bucket 20 empty, the arm 22 will maintain the button 24^a depressed and the circuit closed, as indicated in Fig. 1, for example.

Depending from the underside of casing 10 are the supporting brackets 25, each having the concaved seat or socket portion 25^a and the under cut shoulders 25^b formed by the tapered grooves 25^c. The concavity 25^a furnishes a seat for the pipe 16, and co-acting with each is a locking wedge member 26, having the concaved seat portion 26^a and the tapered shoulders 26^b. When the pipes 16 are seated in the sockets 25^a, the locking members 26 may be driven home into wedged locking relation with the brackets 25, as will be obvious, thus clamping the drain pipes and the associated elements in proper assembled relation with respect to the casing 10 and combustion chamber 12.

With the apparatus properly assembled, should the ignition means fail, liquid fuel will accumulate in the combustion chamber or firepot 12 until it flows out through passages 12^a into the sumps 15, from whence it will be conducted through pipe 16 into the sealing members 17, from one of which it will flow into the bucket 20 until the weight of the fuel therein is sufficient to bend the spring arm 22 downwardly to permit opening of the switch 24, which will discontinue

the actuation of the electrical apparatus. Should fuel leak or accumulate in the casing 10, it will flow out through the port 10^a into the cross pipe 19, and likewise be conducted into the bucket 20. By this means should the ignition fail or should the supply pipe leak, the apparatus will be automatically thrown out of operation, thus obviating further escape of combustible fuel.

- 10 As soon as a small amount of fuel has accumulated in the sealing member 17, draught air or air for combustion will be prevented from escaping through the pipes 16. Should it be desired to cut out the electrical apparatus, the arm 22 may be swung laterally to the position shown in Fig. 11, permitting the switch 24 to open.

In order to remove the drain structure described above, it is merely necessary to release the locking members 26 from wedging relation with brackets 25, after which the pipes 16 and their associated elements may be readily removed for replacement or repair.

- 25 It will be obvious that my invention is susceptible of modification, and I do not wish to be restricted to the form shown and described, except as defined in the appended claims.

30   What I claim is:

- 35 1. In a fuel burning apparatus, a receptacle, means for collecting unburned fuel and conducting it to said receptacle, a switch having means for normally urging it to open, and a flexible arm from which the receptacle depends, said arm being adapted to yieldably hold said switch closed except when said receptacle contains a given weight of unburned fuel.

- 40 2. In a fuel burning apparatus, a receptacle, means for collecting unburned fuel and conducting it to said receptacle, an adjustable support for said means, a switch having means for normally urging it to open, and a flexible arm from which the receptacle depends, said arm being adapted to yieldably hold said switch closed except when said receptacle contains a given weight of unburned fuel.

- 50 3. In a fuel burning apparatus, a receptacle, means for collecting unburned fuel and conducting it to said receptacle, a switch having means for normally urging it to open, and an element from which said receptacle depends, said element being adapted 55 normally to hold said switch closed, to allow said switch to open when said receptacle contains a given weight of unburned fuel, the switch and element being adapted to automatically reset themselves into normal position when the receptacle becomes empty.

4. In a fuel burning apparatus, a receptacle, means for collecting unburned fuel and conducting it to said receptacle, an adjustable support for said means, a switch

having means for normally urging it to open, and a flexible element from which the receptacle depends, said element being adapted normally to hold said switch closed, to allow said switch to open when said receptacle contains a given weight of unburned fuel, the switch and element being adapted to automatically reset themselves into normal position when the receptacle becomes empty. 70 75

5. In a fuel burning apparatus, means for collecting and conveying unburned fuel, an adjustable support for said means comprising an element for attaching the support to a surface, a bearing member integral with said element, a longitudinal tapered recess in said member, and a clamping member having a complementary bearing surface and a complementary tapered projection, said projection being adapted to slide into said recess to provide a slidingly adjustable clamping support for said means, and to allow the easy removal and replacement of said means.

6. In a fuel burning apparatus, a device 90
for collecting and conducting unburned
fuel, and means for adjustably positioning
and supporting said device comprising a
member having a longitudinal channel of
uniform dimension for permitting longitudi- 95
nal adjustment of said device within
and relative to said member, a longitudinally
tapered recess in a portion of said member,
and a clamping member having a longitudinally
tapered projection thereon for engagement 100
with said recess, said clamping member being
adapted for longitudinal slideable engagement
with the first said member for clamping,
positioning, and supporting said device thereinbetween. 105

7. In a fuel burning apparatus, a flexible arm, a receptacle for receiving unburned fuel, a switch having means normally urging it to open, said arm being adapted normally to yieldably hold said switch closed 110 and a portion of said arm being adapted to move downwardly to allow said switch to open when a given weight of unburned fuel is contained within said receptacle.

8. In a fuel burning apparatus, a flexible arm, a receptacle depending from said arm, means for collecting and conveying to said receptacle unburned fuel, and a switch having a projecting element normally urged to open the switch, said arm being adapted to normally contact with said element for holding said switch closed and to move downwardly to allow said switch to open when said receptacle contains a given quantity of unburned fuel, the whole being adapted to reset itself into normal position as soon as the receptacle becomes empty. 115 120 125

In witness whereof, I hereunto subscribe my name to this specification.

HUDSON A. TEDMAN.
